AIRPLANE RIB

Karl Schmidt, United States Navy

Application March 9, 1938, Serial No. 194,886

6 Claims. (Cl. 244—132)

(Granted under the act of March 3, 1883, as
amended April 30, 1928; 370 O. G. 757)

This invention relates to airplane ribs and it has a particular relation to the capstrip portions thereof to which the envelope or covering is secured.

5 Heretofore it has been the practice to attach the fabric covering of an airplane wing to the capstrip of the rib member by a lacing cord looped around the capstrip and cover and knotted at intervals. In this method the fabric cover is 10 stretched over the airfoil frame in contiguous relation to the capstrips of the rib members after which the usual reenforcing tape of a width equal to the capstrip is placed on the cover over the entire length of the capstrip and the two 15 secured thereto by the lacing cord which is looped tightly around the capstrip at intervals.

The principal object of this invention is the provision of an airplane wing rib which is so constructed that the fabric covering may be attached thereto continuously throughout the entire length of the rib, thus avoiding localized strains and insuring that the covering is stretched tightly with evenly distributed tension so that the full strength of the cover fabric may 25 be developed.

Another object of the invention is the provision of an airplane wing rib and a cooperating cover fastening device by means of which the fabric covering, when attached to the wing, will 30 present a smooth cambered surface of high aerodynamic efficiency.

With these and other objects in view, as well as other advantages that may be incident to the use of the improvements, the invention consists 35 in the parts and combinations thereof herein-after set forth and claimed, and with the understanding that the several necessary elements constituting the same may be varied in proportion and arrangement without departing from 40 the nature and scope of the invention, as defined in the appended claims.

In order to make the invention more clearly understood, there are shown in the accompanying drawings, means for carrying the invention 45 into practical use, without limiting the improvements in their useful application to the particular construction, which, for the purpose of explanation, have been made the subject of illustration.

50 In the accompanying drawings:

Fig. 1 is a diagrammatic perspective view showing the method of attaching a fabric covering to the wing in accordance with the invention;

Fig. 2 is a transverse vertical sectional view through an airplane wing;

Fig. 3 is an enlarged vertical sectional view through the capstrip of the improved wing rib; and

5 Figs. 4 to 10 are similar views of different forms of capstrips embodying the invention.

Referring to the drawings and particularly to Fig. 2 thereof, an airplane wing constructed in accordance with the invention is shown as comprising upper and lower capstrips 10 and 11 respectively, secured to fore-and-aft longitudinal beams 12 and 13 and with one another by diagonal bracing members 14. The capstrips 10 and 11 may be of different cross-sectional shapes 15 but in each case the load characteristics are substantially the same.

Fig. 3 illustrates a capstrip of substantially V-shape being formed with an inner vertical flange 15 and outer diverging flanges 16 terminating in 20 inwardly extending edges 17. The fabric covering 18 is flexed into the depression formed by the flanges 16 and secured in position by a longitudinally extending relatively inflexible load-strip 19 which is secured to the capstrip 10 at intervals by screws 20. The covering 18 is preferably reinforced along its line of attachment to the rib 10 by interposing it between layers or plies of fabric 21 and 22, the former disposed along the full length of the capstrip and the latter being 30 wrapped around the load-strip. The load-strip lies wholly within the depression between the flanges and is covered by a sealing tape 23 which is dope cemented to the fabric covering 18 so as to provide a smooth flat surface of minimum 35 wind drag. The warp and woof of the fabric of the plies 21 and 22 preferably extends at an angle to that of the coverings so as to obtain the maximum reenforcing effect. The screws 20 are of the self-lapping type and are screwed into apertures 24 previously bored in the capstrip. The heads 25 of these screws are seated within recesses 26 formed in the load-strip 19 so as to form a flush surface therewith and are formed with pointed ends 27 for entry without rupturing 45 between the threads of the fabric when the load-strip is secured in position.

In Fig. 4 there is shown a modified form of capstrip in which a flat bottomed channel 28 is formed along the outer edge of the rib. This 50 channel is of less depth than the depression shown in Fig. 3 and as a result the load-strip 19 extends a slight distance above the surface of the wing. Also, the sealing tape 23 has been omitted in this form.

In Fig. 5 there is shown another form of the invention in which the capstrip consists of two side plates of similar shape and formed with parallel inwardly extending flanges 29 secured to intermediate spacing members 30 and with diverging outer flanges 31 terminating in inwardly extending edge portions 32. In this form of the invention the fabric covering 18 is secured to the capstrip by a load-strip 33 having diverging side portions 34 disposed at an angle corresponding to that of the flanges 31 and with an intermediate reinforcing rib 35. This rib 35 is recessed at intervals, as indicated at 36, to permit self-tapping fastening screws 37 to be inserted through openings formed in the flanges 31 and 34 of the capstrip and load-strip for engagement with tapping plates 38. As in Fig. 2 the recess in which the load-strip is secured is covered by sealing tape 23. The spacing members 30 are only located at the points along the capstrip where the load-strip is secured thereto, thus lightening the structure. This particular construction is ideally suited for the use of aluminum coated metal. After all of the parts of the capstrip have been shaped to the desired contour, they are readily assembled with the spacer plates 30 by a spot welding process.

In Fig. 6 there is shown a rib construction quite similar to that shown in Fig. 5 in principle. In this construction the inwardly extending flange 39 of the cap-strip is a part of and built into the rib truss and is formed with an enlargement or bead 40 along its outer edge. A plate 41, having outwardly diverging flanges 42 terminating in inwardly projecting edge portions 43, is secured to the flange 39 by self-tapping screws 44 which also secure the load-strip 45 and interposed covering 18 and reinforcing strips 21 and 22 in position. This load-strip is the same as that shown and described in connection with Fig. 5, differing therefrom in that reinforcing rib 35 is omitted.

In Fig. 7 there is illustrated a still further modified form of the invention wherein the capstrip comprises a metal plate bent to form an inwardly extending flange or base 46 of substantially U-shape in cross-section and with outwardly diverging flanges 47 which terminate in inwardly extending marginal edges 48. The structure may be reinforced by gusset plates 49 which are welded to the base portion 46 and flanges 47 at intervals. In this construction the fabric covering 18 and reinforcing strips 21 and 22 are secured in position by a load-strip 50 of triangular cross-section to provide a relatively wide base 51 for engagement with the fabric and a longitudinally extending reinforcing rib 52. This rib is recessed at intervals, as at 53, to receive self-tapping fastening screws 54 which are threaded into drilled openings 55 provided in inserts 56 secured at intervals within the U-shaped portion 46 of the capstrip.

In Fig. 8 there is illustrated a still further modified form of the invention but which is somewhat similar to that described in connection with Fig. 6. In this particular construction the flanges 42 are more or less flexible and are intended to deflect slightly under varying cover loads, as indicated by broken lines in this figure. Also, the fabric cover 18 and reinforcing strips 21 and 22 are held in position under tension by means of a rectilinear loading-strip 57 which is secured to the flange or web 39 by self-tapping screws 58. This construction is designed to facilitate and simplify the forming operations.

In Fig. 9 there is shown another form of cap-

strip which is much the same as the semi-flush type shown in Fig. 4 and may be fabricated by the extrusion process. In this instance the sides of the channel portion 59 are more or less flexible under variable cover loading conditions, as in the structure shown in Fig. 8. It will be noted, however, that a tapping plate 60 is employed at the points of attachment of the loading strip 19 into which the screws 20 are threaded. These tapping plates are inserted in openings 61 formed in the flange or web of the capstrip.

Whereas, the capstrip constructions hereabove described, were specifically designed to withstand negative airloads, it is apparent that such constructions are not necessarily adequately prepared to withstand positive airloading such as normally is imposed on the pressure or underside of the airfoil. When the airplane is sharply maneuvered at high speed, the maximum positive airload is much less than the developed negative pressure, and so the requirement for a suitable capstrip is somewhat different for the purpose.

The structure shown in Fig. 10 was particularly designed to resist such positive airloading of the airplane cover and also for resisting negative airloading. It will be noted that the capstrip in this figure is of substantially T-shape in cross-section being formed with an inwardly extending web 62 and a horizontal flange portion 63 terminating in rounded or inwardly curved edges 64. This form of capstrip may be fabricated by the extrusion process and is well filleted at the juncture of the web and flange components, as indicated at 65. The covering 18 and reinforcing strips 21 and 22 are held in position by a loading-strip 66 having inwardly curved edges 67 which cooperate with the edges 64 of the capstrip in drawing the cover tight and in affording additional rigidity to the structure. As in the structures previously described the loading-strip 66 is secured to the capstrip by self-tapping screws 68.

With particular reference to Fig. 1, the covering is applied to and stretched over the wing panel manually in such manner that the warp and woof threads extend in straight lines both longitudinally and transversely of the wing. The next operation is to depress the fabric into the grooves of the Y-shaped capstrip of the several ribs and to secure it in position therein by the load-strip, the described operation progressing successively from the inboard-rib toward the tip of the wing, as indicated at "a", "b", and "c" in Fig. 1. The original tension on the fabric covering is maintained during this operation by weights W suitably arranged and attached to the marginal edges of the fabric. It will be apparent that as the load-strips are secured in position the fabric will be drawn inwardly and elevate the weights which maintain a constant tension on the fabric. The top and bottom covers of the wing are applied in a like manner, and the leading and trailing edges of the wing are covered with thin sheet metal after which the surfaces are treated with dope to complete the wing.

Other modifications and changes in the proportion and arrangement of the parts, other than those shown, may be made by those skilled in the art, without departing from the nature and scope of the invention, as defined in the appended claims.

The invention described herein may be manufactured and/or used by or for the Government of the United States of America for governmental purposes without the payment of any royalties thereon or therefor.

I claim:

1. An airplane wing rib construction comprising a capstrip having an inwardly extending web portion and an outer channel portion of substantially V-shape in cross-section, and a load-strip of corresponding cross-sectional shape attached to said capstrip for flexing a fabric wing covering into said channel portion and securing it under tension therein, the channel portion of said load-strip having a rib extending longitudinally therealong.
2. An airplane wing rib construction comprising a capstrip having an inwardly extending web portion and outwardly extending diverging flanges forming a depression, and a load-strip formed with outwardly diverging flanges attached to the diverging flanges of said capstrip for flexing a fabric wing covering into said depression and securing it under tension therein.
3. An airplane wing rib construction comprising a capstrip having an inner web portion and a separable outer channel portion having outwardly diverging side flanges, and a load-strip attached to the flanges of said capstrip for flexing a fabric wing covering into said channel portion and securing it under tension therein.
4. An airplane wing rib construction comprising a capstrip having an inwardly extending web portion of substantially U-shape in cross-sec-

tions and outwardly extending diverging flanges forming a depression, inserts fixed in said U-shaped portion at intervals therealong, and a load-strip attached to said inserts for flexing a fabric wing covering into said depression and securing it under tension therein, said load-strip having an outwardly extending rib extending longitudinally therealong. 5

5. An airplane wing rib construction embodying a capstrip comprising two complementary members having parallel portions secured together to form an inwardly extending web and outer diverging portions forming a channel of substantially V-shape in cross-section, and a load-strip corresponding to the shape of said channel attached to said diverging portions for flexing a fabric wing covering into said channel and securing it under tension therein. 10 15

6. An airplane wing rib construction embodying a capstrip comprising two complementary members having parallel portions secured together to form an inwardly extending web and outer diverging portions forming a channel of substantially V-shape in cross-section, and a load-strip having diverging flanges attached to the diverging portions of said members for flexing a fabric wing covering into said channel and securing it under tension therein. 20 25
